UNITED STATES PATENT OFFICE.

LEROY L. RICHARD, OF COALINGA, CALIFORNIA, ASSIGNOR OF ONE-THIRD TO ELI B. MAY AND ONE-THIRD TO CHARLES A. BROWN, BOTH OF COALINGA, CALIFORNIA.

AUXILIARY TABLE.

1,284,776.

Specification of Letters Patent. Patented Nov. 12, 1918.

Application filed July 18, 1917. Serial No. 181,254.

To all whom it may concern:

Be it known that I, LEROY L. RICHARD, a citizen of the United States, residing at Coalinga, in the county of Fresno and State of California, have invented certain new and useful Improvements in Auxiliary Tables, of which the following is a specification.

My invention relates to tables, more especially to those used in ice-cream and refreshment parlors.

The object of the invention is to provide for the comfort and convenience of children in partaking of refreshments, particularly such as are served in glasses, as, for example, ice cream soda and the like.

To this end my invention consists in an auxiliary or supplementary table attached to and adapted to be folded under and to be withdrawn from the main table, said auxiliary table in the act of withdrawal being depressed to and held at a lower level suitable for the children, so that high chairs are dispensed with and the children need not be set apart but may sit in company with their elders.

Referring to the accompanying drawings, Figure 1 is a top plan view of the auxiliary table with its connections, in folded position, as it lies under the main table, the latter being omitted.

Fig. 2 is a side elevation of the same, showing it under and attached to the main table.

Fig. 3 is a side elevation of the same, showing it in its extended and depressed position, the main table being omitted.

In Fig. 2, 1 is the slab or top of the main table.

2, is the auxiliary or supplementary table. In practice it will be relatively small but of a size to conveniently hold a dish or other vessel, such as a glass in which refreshments are served.

To the rim of the small table 2 is secured a bracket 3, with an arm 4, to which is pivoted at 5 an inner pair of links 6, and at 7 an outer pair of links 8.

9 is a winged bracket plate adapted to be secured to and under the main table 1.

10 To the wings of this plate at 10, the other ends of the inner links 6 are pivoted, and to said wings at 11, the outer pair of links 8 are pivoted. To the plate 9, at 12, is secured

one end of a spring 13, the other end of which is secured at 14 to a cross bar 15 of 55 the outer pair of links 8.

The mounting of the auxiliary table enables it to be folded compactly under the main table, as shown in Figs. 1 and 2, the pairs of links snugly nesting and pressing 60 close up under the main table, and the small table pressing close up under the links. The auxiliary table may be unfolded from under the main table and projected or extended 65 from its side, being at the same time depressed to a lower level, as shown in Fig. 3. In these movements the spring 13 assists, and holds the small table against any unintentional pressure.

In order to positively lock the auxiliary table in its extended depressed position, there is fitted under it a sliding latch 16, with a handle 17, and controlled by a spring 18. The free end of this latch is adapted 70 to engage a keeper notch 19 in the extremity 75 of one of the outer links, 8, as shown in Fig. 3.

By grasping the handle 17 of the latch 16, when the auxiliary table is folded under the main table as shown in Fig. 2, and pulling on it, the latch is drawn back and by this pull the auxiliary table is drawn outwardly to the extended depressed position of Fig. 3; and then upon releasing the latch, the latter will spring into its engagement 80 with the keeper notch 19, and the parts will be locked in position. To fold the auxiliary table again, the latch is first withdrawn, and then by pressing on the table, it will move 85 back and up under the main table. 90

In order to hold with greater security the refreshment glass upon the small auxiliary table, there is pivoted at 20 to the arm of the bracket 3, the spring arm bracket 21, which will readily admit and hold the glass 95 stem.

By carrying and suspending the auxiliary table by the double pairs of links 6 and 8, and so proportioning them with regard to their lengths and to their distances between 100 their relative and respective pivotal points on both tables, the auxiliary table is always and positively held horizontal and in no danger of tipping even though the latch should be accidentally disengaged. This arrangement is one in which the distance 105 5—7

is equal to the distance 10—11 and the distance 5—10 is equal to the distance 7—11 as shown in Fig. 3.

I claim:

- 5 1. In combination with a main table, an auxiliary table; a bracket member secured to the rim of the auxiliary table at its rear portion; a pair of links pivoted on opposite sides of the rear portion of the bracket member 10 and thence diverging forwardly; a second bracket member secured under the main table near its rim; pivotal connections on opposite sides of the inner portion of the second bracket member with the forward ends of 15 the links; a second pair of links pivoted on opposite sides of the forward portion of the first bracket member and thence diverging forwardly between the first pair of links; pivotal connections on opposite sides of the 20 outer portion of the second bracket member with the forward ends of the second pair of links; and a spring controlling the movements of said links in extending and retracting the auxiliary table.
- 25 2. In combination with a main table, an auxiliary table; a bracket member secured to the rim of the auxiliary table at its rear portion; a pair of links pivoted on opposite sides of the rear portion of the bracket member 30 and thence diverging forwardly; a second bracket member secured under the main table near its rim; pivotal connections on opposite sides of the inner portion of the second bracket member with the forward ends of 35 the links; a second pair of links pivoted on opposite sides of the forward portion of the first bracket member and thence diverging forwardly between the first pair of links; pivotal connections on opposite 40 sides of the outer portion of the second bracket member with the forward ends of the second pair of links; a cross-bar extending between the first pair of links; a spring secured to the second bracket member and 45 to said cross-bar, to control the movements of the links in extending and retracting the auxiliary table; and means for locking the

links in the extended position of the table.

3. In combination with a main table, an auxiliary table; associated connections for 50 folding the auxiliary table under the main table to be parallel with and adjacent to the under surface of said main table and extending it therefrom to a horizontal plane below its folded position; means for locking the auxiliary table in its extended depressed position; and means pivotally associated with said folding connections and overlying the auxiliary table for holding a vessel on said auxiliary table. 55

4. In combination with a main table, an auxiliary table; pivoted spring controlled links connecting the two tables for folding the auxiliary table under the main table to be parallel with and adjacent to the under 60 surface of said main table and extending it therefrom to a horizontal plane below its folded position; and a spring controlled latch slidably mounted under the auxiliary table and adapted to engage a keeper notch 65 in one of the links to lock said table in its extended depressed position. 70

5. In combination with a main table, an auxiliary table; a double pair of pivoted, 75 spring controlled links connecting the two tables and positioned for folding one pair within the other, said links adapting the auxiliary table for folding under the main table to lie parallel with and adjacent to the under surface of said main table and for being extended therefrom to a horizontal plane 80 below its folded position; and a spring controlled latch slidably mounted under the auxiliary table and adapted to engage a keeper notch in one of the links, to lock 85 said table in its extended depressed position.

In testimony whereof I have signed my name to this specification in the presence of two subscribing witnesses.

LEROY L. RICHARD.
